UNITED STATES PATENT OFFICE.

EMMETT B. MAXWELL, OF BAKERSFIELD, CALIFORNIA.

SOLAR HEATER.

Application filed July 9, 1925. Serial No. 42,561.

This invention relates to solar heaters, and more particularly to that type controlled by an escapement maintaining the heater at all times in proper alignment with the sun.

5 An important object of the invention is to provide a device of this character permitting ready disconnection of the escapement apparatus from the heater proper, so that the heater may be returned to its starting position or be thrown out of operation at any time.

A further object of the invention is the production of a device of this character which may be very readily and cheaply 15 manufactured, which will be durable and efficient in service and a general improvement in the art.

The invention further resides in the details of construction, mounting and operation of the various parts hereinafter described and disclosed in the accompanying drawings, wherein:—

20 Figure 1 is a side elevation showing apparatus constructed in accordance with my invention;

25 Figure 2 is an end elevation thereof and showing the escapement mechanism for controlling the mirror;

30 Figure 3 is a plan view of the escapement control element;

35 Figure 4 is a section on the line 5—5 of Figure 4; and

Figure 5 is a detailed plan view of a portion of the base showing the manner of shifting the base to permit disengagement of the rack and gear.

Referring now more particularly to the drawings, the numerals 10 and 11 indicate base supports in one of which is secured a 40 pipe 12 having its outer end closed, as at 13, and its inner end communicating with a drum or cylinder 14. In the support 11, a stationary conduit 15 is mounted, the inner end of which projects through a stuffing box 16 formed upon the end of the drum. The drum is provided with a steam dome 17 having a safety valve 18 and a steam outlet conduit 19.

Rotatably mounted upon the pipe 12 and 45 stuffing box 16 are the end members 20 and mirror support 21 which is arcuately curved with the axis of the drum 14 as a center. The inner face of this mirror support has secured thereto a multiplicity of mirror segments 22 all positioned to direct reflected

rays against the drum 14. The outer surface of the mirror support has secured thereto a rack 23 extending from one longitudinal edge of the mirror support to the other thereof and at right angles to the axis 60 of the support. Mounted beneath the mirror support is a base 24, one end of which is pivoted, as at 25, and the other end of which has means, as at 26, for locking the same in adjusted positions about the pivot. Upon 65 this base is mounted driving mechanism for maintaining the mirror face of the mirror support in alignment with the rays of the sun.

This timing mechanism includes a support 27 arising from the base 24 and having at its upper ends diverging arms 28 and 29. Between the arms 28 is rotatably mounted a spring drum 30 having a coiled operating spring 31 arranged interiorly thereof and 70 formed with a gear 32 upon its exterior which in one position of the base 24 meshes with the rack 23. Between the arms 29 is mounted a gear 33 having secured thereto a pinion 34, the pinion 34 meshing with the gear 32 of the spring drum. The teeth of the gear 33 are relatively narrow transversely and coacting with an escapement mechanism including a rock shaft 35 rotatably mounted in supports 36 carried by the base 75 24. One end of this rock shaft projects beneath the gear 33 and is provided with an escapement head 37 having a single groove 38 formed therein and extending at a slight angle to the axis of the shaft. The opposite 80 end of the shaft has secured thereto a pendulum 39, the upper end of which is provided with an extension 40 having an adjustable balance weight 41 thereon.

It will be understood that tendency to rotation of the drum 30 under the influence of the spring will be transmitted through the pinion 34 to the gear 33. When the pendulum is shifted so that the outer end 42 of the groove aligns with the teeth of the gear 33, a tooth will enter this groove and in passing the groove will cause the rock shaft to be shifted and the pendulum to move to one limit of its swing. As the tooth escapes from the inner end 43 of the groove, a second tooth of the gear comes in engagement with the end face 44 of the escapement head and rotation of the gear 33 is checked until the shaft 35 is rocked under the influence of the pendulum and the outer end 42 of the 90 100 105 110

groove 38 again aligns with the gear teeth of the gear 33. It will be obvious that the speed of oscillation of the pendulum will depend upon the position of the shifting weight 41 and accordingly this weight forms a governor for the timing mechanism. As the gear 33 is permitted to rotate, the drum 30 likewise rotates and its teeth 32 will transmit motion to the mirror support 21 through the rack 23, causing this mirror support to shift and maintain its proper position with relation to the sun. At the end of the day's run, the mirror support may be shifted into position for the next day's run by releasing the member 26 to permit the base to be shifted until the gear 32 disengages from the rack 23 and after the drum has been properly positioned, the gear may be re-engaged.

20 The apparatus is at present shown as operatively connected with a pump 45 of the steam ejector type, the barrel 46 thereof receiving the steam inlet pipe 49 which is connected to the steam conduit 19 through a control valve 51. Where a pump is operated by the steam generated, a portion of the discharge water may be withdrawn from the pump tubing 52, as at 53, and discharged to a storage tank 54. This storage tank 54 may communicate with the drum 14 through a conduit 55 and injector 56 which may receive its steam from a valve-controlled branch 57 of the conduit 19. While the

pump is shown and described as used in conjunction with the apparatus, it will, however, be obvious that any other suitable mechanism might be operated by the generated steam or this steam might be put to any other use.

35 Since the construction hereinbefore set forth is capable of a certain range of change and modification without materially departing from the spirit of the invention, I do not limit myself to such specific structure except as hereinafter claimed.

40 I claim:

A steam generator comprising an arcuately curved solar mirror, a stationary drum having its axis located at the focal line of the mirror, pendulum controlled means for turning the mirror about the axis of the drum to maintain the face thereof toward the sun, spring means for actuating the pendulum controlled means and a mounting 50 for said pendulum controlled means permitting adjustment thereof to engage or disengage the mirror comprising a base upon which the pendulum means is mounted, a pivot engaging one end of the base and about which the base is swingable and a securing means for the base extending through an arcuate slot formed in the opposite end of the base.

55 In testimony whereof I hereunto affix my signature.

60 EMMETT B. MAXWELL.
